(57) **CLAIM**

The ornamental design for a microphone for wireless communication device, as shown and described.

DESCRIPTION

FIG. 1 is a left and front perspective view of a microphone for wireless communication device showing the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines in the drawings are for the purpose of illustrating portions of the microphone for wireless communication device that form no part of the claimed design.

1 Claim, 7 Drawing Sheets
